L. L. WILSON.

RAILWAY TIE.

APPLICATION FILED OCT. 21, 1918.

1,293,598.

Patented Feb. 4, 1919.

UNITED STATES PATENT OFFICE.

LYDELL L. WILSON, OF EAST RANDOLPH, NEW YORK.

RAILWAY-TIE.

1,293,598.

Specification of Letters Patent.

Patented Feb. 4, 1919.

Application filed October 21, 1918. Serial No. 258,927.

To all whom it may concern:

Be it known that I, LYDELL L. WILSON, a citizen of the United States, residing at the village of East Randolph, in the county of Cattaraugus and State of New York, have invented certain new and useful Improvements in Railway-Ties, of which the following, taken in connection with the accompanying drawings, is a specification.

10 The invention relates to railway track construction; and the improvements consist, first, in providing a pan-shaped concrete tie or one in which the bottom side of the tie is smaller than the top having sides inwardly 15 inclined toward the bottom so that said tie will lift freely from its pan-shaped bed, which pan-shaped or inclined sided beds or openings are provided in the concrete base and lined with paper or some equally good 20 separating material between said concrete tie and base so that said tie may be lifted from its bed for repair or attaching the insulating wood blocks thereto upon which the rails are secured; and second, in providing a strong 25 metal eye which is embedded in the concrete tie near each end for raising the same, a combined lifting bar and tripod being also provided having a hook to engage said eye, by means of which said concrete tie may be 30 raised from its seat and turned and supported upon a pair of said lifting bars and tripods so that the insulating blocks may be attached to said concrete tie while in the inverted position or it may be raised for renewal or adjustment of said block and the 35 parts attached thereto; and the invention consists of the novel features and combinations herein after set forth and claimed.

In the drawings, Figure 1 is a perspective 40 view of a concrete tie with a metal eye embedded therein near each end to elevate the same; and Fig. 2 is a sectional view of a portion of the concrete base and tie embedded therein with a separating medium between said tie and base. Fig. 3 is a sectional view of a portion of the concrete base showing the opening therein for the tie, said tie being shown supported upon an elevating bar alongside said opening. Fig. 4 is a side 45 elevation of the elevating bar showing the hook and tripod brace attached thereto; and Fig. 5 is an elevation showing the triangular shape of the tripod brace and its attachment to the elevating bar. Fig. 6 is a lengthwise 50 sectional view of an end portion of the tie.

Like characters of reference refer to corresponding parts in the several views.

The numeral 10 designates the concrete paving base which has the pan-shaped openings 11, that is, the openings having inclined 60 sides diminishing downwardly, which opening 11 is lined with paper or other separating material 12.

The numeral 13 designates the concrete railway tie which has the similarly inclined 65 sides which diminish the size of the tie 13 toward its bottom so that it fits within the opening 11. In making the concrete tie 13 the metallic eyes 14 which have split ends 15 are embedded one near each end of said tie 70 and are so placed that each eye faces the side of the tie so that a tool may be inserted through the eye 14 for raising the tie 13 from the bed 10.

A crosswise opening 16 is preferably provided near each end of the top of the tie 13 to receive therein the insulating block 17 which is preferably of wood. The block 17 is attached to the tie 13 by means of the bolts 18 which extend down through each end of 80 each block 17 and through the tie 13 into an opening 19 in the bottom of said tie 13 to receive the attaching nut 20 within said opening 19. The opening 19 may be made to fit the nut 20 so as to hold it firmly in position beneath the hole for the bolt 18 in the cement tie 13 so that said bolts 18 may be inserted or removed from the upper side of the tie 13 without access to the lower side of said tie. 90

The tie 13 is elevated preferably by means of a lifting bar 21 which has the hook 22 attached to said bar a predetermined distance from the point 23 thereof, which hook 22 is made sufficiently strong to support the tie 95 13 when inserted through the strong eye 14 in the tie 13. Said distance from the point 23 is so proportioned that said point 23 will extend out onto the top of the concrete base 10 alongside the opening 11 so that a pair 100 of lifting bars 21 may have the hooks 22 inserted through the eyes 14 at each end of the tie 13 and said tie may be easily lifted out of the opening 11, though such a concrete tie weighs about four hundred pounds. 105

In order to hold the tie in the elevated position, a triangular brace 24 is attached to the opposite side of the bar 21 from the hook 22 by means of an eye or loop 25 to thereby form a tripod with the point 23 of the lifting 110

bar 21. The brace 24 is preferably in triangular form and has the two points or spuds 26 extending down therefrom to engage in the top of the concrete base 10, and 5 two bars 21 form two tripods one at each end of the tie 13 which easily support the tie 13, as shown in endwise elevation in Fig. 3, so that the blocks 17 may be removed when worn or impaired for any reason and fresh 10 blocks supplied thereby providing a concrete tie which may be removed at low cost and a railway bed construction which will last indefinitely, and also providing a model support for the rail. The holes 27 are provided in the blocks 17 for attaching the rails 15 to the tie.

It is apparent that the splitting of the end 15 of the shank of the metallic ring 14 enlarges said shank within the concrete tie 20 13, thereby giving it a strong holding engagement with said tie so that it can be lifted from its bed in the opening 11 in the concrete base 10 by any suitable instrument.

I claim as new:—

- 25 1. A railway tie having sides inwardly inclined toward the bottom in combination with a concrete paving base having a similar shaped opening therein to conformably receive said tie.
- 30 2. A railway tie which is smaller at the bottom than at the top in combination with a concrete paving base having a similar shaped opening therein to conformably receive said tie.

Copies of this patent may be obtained for five cents each, by addressing the "Commissioner of Patents, Washington, D.C."

3. A railway tie which is smaller at the bottom than at the top in combination with a concrete paving base having a similar shaped opening therein to conformably receive said tie, and a separating medium between said tie and base.

4. In railway construction, a concrete base having an opening therein with outwardly and upwardly inclined sides, a lining for said opening, a railway tie having inclined sides to fit within said opening; and means 45 on said tie for holding engagement therewith to elevate the same from said opening.

5. In railway construction, a concrete base having a pan shaped opening smaller at the bottom than at the top, a lining for said 50 opening, a concrete tie removably fitting within said opening, and a metallic eye embedded in each end of said tie to raise the same from said opening.

6. In railway construction, a concrete base 55 having an opening therein, a concrete tie removably received in said opening, metallic eyes embedded in said concrete tie in spaced relation to raise the same, said metallic eyes each having an enlargement on the opposite 60 end of its shank from the eye to give holding engagement therefor within said concrete tie.

In testimony whereof I have affixed my signature in the presence of two witnesses.

LYDELL L. WILSON
